WRAPPING MACHINE

Maurice Krafft, Lausanne, Switzerland, assignor
to the firm Sapal Société Anonyme des Plieuses
Automatiques, Lausanne, Switzerland

Application August 24, 1937, Serial No. 160,667
In Switzerland September 1, 1936

5 Claims. (Cl. 93—2)

The present invention relates to wrapping-machines for wrapping articles the transverse sectional area of which varies over the length of the article, such as for instance sweet meats, chocolates, de luxe bonbons and like articles. 5 Heretofore articles of this kind have been usually wrapped by hand owing to their particular shape and the required high quality of wrapping.

It is an object of the present invention to 10 place this manual work by automatic operations performed on a wrapping machine whereby, at the same time, the required amount of wrapping material is limited to a minimum.

Machines for wrapping articles having a varying transverse sectional area over their length are 15 already known in which folding tools apply a sheet of wrapping material around the article in such manner that the sheet is shaped to a straight tube which is tangential to the article along the periphery of that transverse sectional area thereof which has the greatest diameter.

According to the present invention the wrapping is effected at a plurality of stations at each 20 of which one wrapping tool at least is arranged 25 to be approached to and removed from the article, to apply the tube-shaped wrapping sheet against those portions of the article having a smaller diameter than the tube-shaped sheet, and a plurality of cam controlled gripping devices provided with clamping jaws are arranged 30 to simultaneously engage the articles situated at the various stations, to be displaced in a direction substantially parallel to the opening and closing movement of the jaws for bringing each 35 article to the next following station, to be opened and removed from the articles in a direction at right angles to the direction of movement of the clamping jaws, to be returned to the preceding stations in a direction parallel to the movement 40 of the clamping jaws, and again to approach the articles for engaging each a new article. The working surface of the tools which adapt the tube shaped wrapping sheet on the article preferably forms a negative of the surface portion of the 45 article against which the sheet is applied, so that these tools effect a wrapping operation while gripping an article at one of the operating stations and transporting it to the following station.

The accompanying drawings illustrate a preferred example of a wrapping machine according to the invention.

Figure 1 shows in diagrammatic manner a plan view of a part of the wrapping machine.

Figure 2 is an elevation thereof.

Figures 3 and 4 show a plan view and an eleva-

tion, respectively, of the machine in another phase of operation, and Figures 5 and 6 are similar views of the machine in a third phase of operation.

Figure 7 shows a detail in section drawn to a 5 larger scale.

Figure 8 is a section along the line 8—8 of Fig. 1.

Figs. 9, 10 and 11 show each a cam actuated control device of three different movable members 10 of the wrapping machine.

In Figs. 1 and 2 the article 3 to be wrapped is brought by conveying members, not shown, to a vertically movable carrier 1. This carrier is slidably mounted in a fixed guide member 52 and is connected to one end of a lever 53 rotatably 15 mounted on a rod 40, while the other end of the lever carries a cam follower 54 urged against a cam 55, secured to a shaft 56 (Fig. 9), by a spring 14. A sheet of wrapping material 2, as for example a sheet of aluminium foil, is delivered in 20 any known manner upon the article 3. A vertically movable plunger 1a is slidably mounted on a guide member 57 and connected to one end of a lever 58 rotatably mounted on the rod 40, while the other end of the lever carries a cam follower 25 59 urged against a cam 60, secured to the shaft 56 (Fig. 10), by a spring 15. This plunger 1a is lowered on the wrapping sheet 2 and the article 3. The carrier 1 and plunger 1a then effect a simultaneous upward movement to the level of 30 35 a horizontal table 5. The article with the wrapping sheet 2 is thus drawn across folding members 4 and 4a which fold the sheet downwards (Fig. 4) so that it obtains the shape of a reversed U.

The folding member 4a is adjustable in horizontal direction, so as to pass beneath the article in order to effect a folding operation as will be described hereinafter. For this purpose, the folding member 4a is mounted at one end of a 40 lever 61 rotatably mounted at 62 on the frame of the machine, and the other end of the lever is connected to a rod 63 in turn connected to a lever 64 which is pivotally mounted at 65. This lever 64 carries a cam follower 66 urged against a cam 45 67, secured to a shaft 68, by means of a spring 76. The first operation of the wrapping is now finished and the place at which this operation has been effected will be designated by station A. The previously arrived articles are now situated 50 on the various stations B, C, D on the table 5.

Above the table 5 is disposed a double guide rail 6, situated in a plane parallel to the table 5, and carrying two independently movable slides 7 and 8, the first one being disposed along the upper 55

face, and the second along the lower face of the rail 6, and both slides being connected to control cams 30 and 31 by the intermediary of the rods 14 and 15 and the levers 32 and 33, rotatably mounted at 34 and 35, respectively, and carrying cam followers 36 and 37.

A vertical guide rail 9, rigid with the frame of the machine, carries a slide 10 to which is secured an arm 11 extending parallel with the guide rail 6. This latter rail 6 is movable in a transverse direction relative to the table 5, and is carried by a slide 20 movable along a guide 19. The slide 10 is controlled by a lever 17 movable about the axis 18, and the slide 20 is moved by a rod 21. The lever 17 is connected by means of a rod 38 to a lever 39 rotatably mounted at 40 and carrying a follower 41 applied against a cam 42. The rod 21 is connected to a lever 44 rotatably mounted at 45 and carrying a follower 46 held in contact with a cam 47.

Three gripping and conveying members comprise each a pair of clamping jaws 22, 23 and 24, respectively. The right hand jaws of each pair are secured to the upper slide 7, and the left hand jaws to the lower slide 8. The three clamps accordingly open and close together. The various cams control the movement of the gripping members in such manner, that when the three pairs of jaws are open, they can be moved backwards by the slide 20 (Fig. 3), then the rods 14 and 15 move them towards the left, and the slide 20 again moves them forwards; afterwards the rods 14 and 15 move relatively to each other to simultaneously close the three pairs of clamps on the articles situated at the various stations (Fig. 5), and finally the three gripping members move simultaneously towards the right to bring the articles to the next following stations.

The jaws 22 and 24 are provided with plane clamping faces which may be coated with a soft material, while the jaws 23 have a working surface which forms a negative of the surface portion of the article engaged by these jaws.

The arm 11 carries two slidable plungers 12 and 13 subjected to the action of springs which push the plungers downwardly. The plunger 12 is situated above the station B and is provided with a contacting face which may be applied on the article to maintain the latter at the station, when the gripping members are removed from the article. At this station B acts a folding tool 25 which is vertically movable and can penetrate through an opening in the table 5, in order to apply the front and rear ends of the sheet 2 against the article. The tool 25 is slidably mounted in a guide 69 and is connected to one end of a lever 70 rotatably mounted on the rod 40, while the other end of the lever carries a cam follower 71 urged against a cam 72, also secured 60 to the shaft 56, by means of a spring 78 (Fig. 11).

The plunger 13 is provided with a contacting surface 26 forming a negative of the surface portion of the article against which the plunger is applied. The plunger 13 is hollow and traversed by a spindle 27 which is movable relative to the plunger and also urged downwardly by a spring 28.

The plunger 13 traverses the arm 11 and is secured to a rod 49 to which is attached one end of a spring 50 having its other end connected to the arm 11. The rod 49 is guided in a fork 51. When the arm 11 moves downwardly, the surface 26 forming a mold, is applied on an article, and while the arm 11 continues to move, the plunger 75 13 is raised relatively to the arm and tensions the

spring 50 which thus yieldingly urges the mold against the article.

The spindle 27 maintains the article in its position when the jaws 23 or 24 open and the mold 26 is applied to or removed from the article.

The cams which control the movements of the described folding tools and other movable members are disposed in two groups. The cams 42, 47, 55, 60 and 72 are mounted on a shaft 56, while the cams 30, 31 and 67 are mounted on a shaft 68. The two shafts are connected to each other by means of gears 73 so that they rotate in synchronism. The shaft 68 may be connected to any convenient power source, not shown.

The article to be wrapped and represented by 15 way of example has the shape of a miniature bottle having a bulbed side and a flat side, which shape, until now, required to be wrapped by hand, or, when using a wrapping device with wiper members, required an unusually large amount of 20 wrapping material.

The operation of the machine will be readily understood from the following description of the passage through the machine of an article 3 to be wrapped.

In Fig. 2 an article 3 is disposed on the carrier 1, a sheet of wrapping material 2 is laid on the article and the plunger 1a lowered to hold the sheet in position on the article. Raising of the carrier 1 and plunger 1a brings the article on 30 the level of the table 5 while passing between the folding members 4 and 4a which fold the sheet downwards about the article as shown in Fig. 4. These operations are performed at the station A.

The jaws 22, 23 and 24 are then in the position shown in Fig. 3. They are now moved towards the left, so that the jaws 22 arrive behind the station A, and then all the jaws are moving forwards and are closed, to arrive in the position 40 shown in Figs. 5 and 6, the jaws 22 having gripped the article 3 situated at the station A. At this moment the carrier 1 and plunger 1a are retracted, towards below and towards above, respectively, and the movable folding member 4a 45 moves towards the right beneath the article to fold the left side of the wrapping sheet 2 against the bottom face of the article (Fig. 6). All the jaws are now moved towards the right, so that the jaws 22 bring the article 3 to the station B. 50 While the article passes over the edge of the table 5 carrying the folding member 4, the right side of the wrapping sheet 2 is also applied towards the bottom face of the article, so that when the article arrives at the station B, the sheet 2 is wrapped around the article in the shape of a straight tube which is tangential to the article along that circumference having the greatest diameter. The arm 11 is then lowered to apply the plunger 12 against the article, the 60 jaws 22, as also the jaws 23 and 24, are opened and retracted from the article, while the folding tool 25 is raised and passes across the opening in the table 5 to apply the front and rear ends of the sheet 2 against the article. The tube-shaped 65 wrapping sheet has thus received its first deformation. The jaws now move towards the left again and then forwards, so that the jaws 23 grip the article at the station B, while the jaws 22 grip a new article at the station A. The holding 70 plunger 12 is now raised and the jaws moved towards the right so that the article gripped at the station B is moved to the station C. During this transfer of the article to the station C the jaws 23, the clamping surfaces of which correspond to 75

the shape of the article, apply the lateral portions of the tube-shaped wrapping sheet against the surface of the article. At this station the spindle 27 is lowered on the article to hold the same in place while the jaws are retracted. The plunger 26 is now lowered and applies the upper portion of the wrapping sheet towards the surface of the article. The wrapping of the article is now completed. The jaws are again moved towards the left and then advanced, so that the jaws 24 grip the article at the station C after the plunger 26 has been raised. Then the spindle 27 is also raised and the jaws moved towards the right to carry the article to the station D on a conveyer band 16 which removes the completely wrapped article from the machine.

It will be understood that the number of the stations can be smaller or greater, according to the shape of the article to be wrapped. Also, the 20 wrapping members could move along inclined planes instead of moving horizontally or vertically, and the clamping jaws could effect a movement of rotation instead of moving rectilinearly in a plane.

25 An advantage of the described machine is realized by the fact that articles of nonprismatic shape can be completely wrapped by first rolling the wrapping material to the shape of a straight tube around the article, this rolling operation being the base of every high quality wrapping, as it is also made when wrapping articles by hand, and permitting the use of a sheet of minimum size.

I claim:

35 1. In a wrapping machine for wrapping articles having transverse sectional areas of varying diameter, a plurality of operating stations at which the wrapping is effected, means operable at the first of said stations for folding a sheet of wrapping material around the article to the shape of a straight tube disposed tangential to the article along the circumference of that transverse sectional area thereof having the greatest diameter, and a plurality of grippers for moving the articles from one operating station to the next following station, one at least of said grippers having gripping surfaces of a shape corresponding to a portion of the shape of the articles to be wrapped whereby said gripper, upon gripping an article partially wrapped in said tube-shaped wrapping sheet to carry the article from one station to the next following station, simultaneously performs a wrapping operation by applying a portion of the tube-shaped wrapping sheet against 55 that surface portion of the article corresponding to the shape of the gripping surfaces.

2. In a wrapping machine for wrapping articles having transverse sectional areas of varying diameter, a plurality of operating stations at which the wrapping is effected, means operable at the first of said stations for folding a sheet of wrapping material around the article to the shape of a straight tube disposed tangential to the article along the circumference of that transverse section thereof having the greatest diameter, a plurality of grippers for moving the articles from each operating station to the next succeeding station, said grippers being operable to grip an article at one station, to transfer the article to the next succeeding station and then to return to the preceding station, and holding means operable in timed relationship with said grippers to hold the articles at the operating stations when not engaged by the grippers, one of said grippers 75 having gripping surfaces forming a negative of

a portion of the surface of the article to be wrapped whereby said gripper, upon gripping an article partially wrapped in said tube-shaped sheet to transfer the article to the next succeeding station, simultaneously performs a wrapping operation by applying a portion of the tube-shaped wrapping sheet towards the surface of the article.

3. In a wrapping machine for wrapping articles having transverse sectional areas of varying diameter, a plurality of stations at which the wrapping operations are successively effected, means operable at the first of said stations for folding a sheet of wrapping material around the article to the shape of a straight tube disposed tangential to the article along the circumference of that transverse section thereof having the largest diameter, a plurality of grippers for moving the articles from each operating station to the next succeeding station, one of said grippers having gripping surfaces forming a negative of a portion of the surface of the article to be wrapped whereby said gripper, upon gripping an article partially wrapped in said tube-shaped sheet to transfer the article to the next succeeding station, simultaneously performs a wrapping operation by applying a portion of the tube-shaped sheet towards the surface of the article, and a plunger actuated wrapping tool operable at the station to which said gripper transfers the article 20 to be wrapped, said wrapping tool having a surface forming a negative of another surface portion of the article for applying the tube-shaped wrapping sheet to a portion of the surface of the article not acted upon by said gripper.

4. In a wrapping machine for wrapping articles having transverse sectional areas of varying diameter, a plurality of stations at which the wrapping operations are successively effected, means operable at the first of said stations for folding a sheet of wrapping material around the article to the shape of a straight tube disposed tangential to the circumference of that transverse section of the article having the largest diameter, a plurality of grippers for moving the articles from each operating station to the next succeeding station, one of said grippers having gripping surfaces forming a negative of those portions of the surface of the article engaged by the gripping surfaces whereby said gripper, when gripping the article partially wrapped in said tube-shaped wrapping sheet for carrying the article from one station to the next succeeding station applies a portion of the tube-shaped wrapping sheet towards the surface portions of the article engaged by the gripper, a wrapping tool operable at that station to which said gripper carries the partially wrapped article, a hollow plunger carrying said tool, means operable in timed relationship with the grippers for reciprocating said plunger 40 and tool towards and away from said partially wrapped article in a direction perpendicular to the plane of movement of the grippers, and a resilient holding spindle slidably within said hollow plunger and adapted to hold said article in 45 position when released by the gripper.

5. In a wrapping machine for wrapping articles having transverse sectional areas of varying diameter, a plurality of stations at which the wrapping operations are successively effected, means operable at the first of said stations for folding a sheet of wrapping material around the article to the shape of a straight tube disposed tangential to the circumference of that transverse section of the article having the largest diameter, a plu- 70

rality of grippers for moving the articles from each operating station to the next succeeding station, each of said grippers including a pair of clamping jaws, a reciprocable slide carrying one of the jaws of each pair of jaws, a second reciprocable slide carrying the second jaw of each pair of jaws, cam means controlling the movement of the slides and operable to cause the slides to move together for reciprocating the grippers between succeeding stations and to cause the slides to move in opposition to each other for opening and closing the jaws, means for moving

5 said slides in a direction perpendicular to the movement imparted by said cam means for removing the grippers from and approaching them towards the articles at said stations, one of said grippers having gripping surfaces forming a negative of those surface portions of the article engaged by the gripper whereby said gripper, upon gripping and transporting the article partially wrapped in said tube-shaped sheet applies a portion of the sheet towards the surface portions of 10 the article engaged by the gripper.
